THOMAS H. LIBBEY, OF SOUTH BEND, INDIANA, ASSIGNOR TO THE STUDEBAKER CORPORATION, OF SOUTH BEND, INDIANA, A CORPORATION OF NEW JERSEY

SPRAYING MACHINE

Application filed September 24, 1927. Serial No. 221,808.

This invention relates to means for applying protective coatings to articles of manufacture and particularly to a machine for spraying the interiors of metallic articles, 5 such as internal combustion engine pistons and the like.

It is common practice with most manufacturers of internal combustion engines to provide the surfaces of cast parts, such as 10 pistons and crank cases which come in contact with the lubricating oil, with a protective coating of some substance such as paint or lacquer. It is well known that when metallic parts are cast, that blow holes and 15 imperfections occur which usually have deposits of moulding sand therein, and it has been found that regardless of the amount of shaking and knocking of the casting, there is always some sand left in the blow holes 20 which will drop out only after the part has had considerable use. This is particularly true with engine pistons, as the sand drops out of the blow holes into the lubricating oil and flows with the oil to the engine 25 bearings and has a disastrous effect thereon, hence, the inner surfaces of the pistons are usually coated with lacquer or some such substance which coats the surfaces and con- 30 gels in the blow holes to prevent the sand from working loose.

So far as applicant is aware, he is the first to provide a machine for successfully spraying the pistons and other articles for quantity production and in a manner so that 35 all parts of the interior thereof could be reached by the spray as the piston bushing bosses usually obstructed the spray stream.

It is therefore, the principal object of 40 the present invention, to provide a new and novel means for holding a plurality of articles and for spraying the interiors thereof with a coating substance.

Another object is to provide a machine 45 for holding a plurality of articles and for

spraying the interiors thereof, with a coating substance, the machine being provided with a rotary portion adapted to receive and rotate the articles to be sprayed.

Another object is to provide a machine 50 for holding pistons while the interiors thereof are being sprayed with a coating substance, said machine having a plurality of openings in a rotary portion for receiving the pistons and having a nozzle adapted to 55 direct the spray stream through each of the openings into the interior of each piston as it passes thereover.

Another object is to provide a machine 60 for holding pistons and for spraying the interiors thereof comprising a supply tank containing a liquid coating substance, a rotary cover for the tank provided with a plurality of openings arranged in a circle for receiving the pistons to be sprayed, a 65 nozzle positioned below the center line of the circle of openings and a pumping means for drawing the coating substance from the tank and forcing the same through the nozzle so that it is directed into the interior of each 70 piston as it passes over the nozzle.

These being among the objects of the present invention, the same consists of certain features of construction and combinations of parts to be hereinafter described with reference to the accompanying drawings, and then claimed, having the above and other objects in view. 75

In the accompanying drawings which illustrate a suitable embodiment of the present 80 invention,

Figure 1 is an elevation showing the spraying machine and the pumping mechanism therefor.

Figure 2 is a plan view of the machine 85 and pumping mechanism shown in Figure 1.

Figure 3 is a section taken approximately on the line 3—3 of Figure 2.

Figure 4 is a section taken on the line 4—4 of Figure 3. 90

Referring to the accompanying drawings, in which like numerals refer to like parts throughout the several views, the piston spraying machine comprises a large circular tank 10, having an inturned marginal flange 11 around its upper edge, and having a circular band 12 therearound. The band 12 is Z shaped in section and is supported on the tank 10 by its upper inwardly extending flange 13 which seats on the flange 11 of the tank 10. The lower flange of the band 12 extends horizontally outwardly to provide a runway 14 for supporting the rotary cover for the tank 10.

The rotary cover is positioned concentrically with and above the tank 10 and consists of a metal shell having a top 15 of greater diameter than the tank 10, and having sides 16 extending downwardly to enclose the upper portion of the tank 10. The marginal edge 17 of the sides 16 is bent inwardly and downwardly toward the tank for a purpose which will be described later. Inside the cover and secured to the sides 16 thereof is an annular plate 18 to which are secured a plurality of spaced brackets 19 having vertically positioned rollers 20 mounted thereon to ride upon the runway flange 14 of the band 12 in order to support the rotary cover. Spaced between the brackets 19 are brackets 21 having horizontally positioned rollers 22 mounted thereon which roll against the vertical face of the band 12 to keep the cover centered on the tank 10.

Arranged in a circle concentrically with the cover top 15 are a plurality of cups 23 which extend below the surface of the top 15 through openings formed therein. The cups 23 are supported by integral flanges 24 which seat upon the metal of the top 15 surrounding the openings. Apertures 25 are provided in the bottoms of the cups 23 to provide unobstructed passageways to the interior of the tank 10. The cups 23 receive the articles to be sprayed with a coating substance and as shown for example in Figures 1, 2 and 3, unmachined internal combustion engine pistons 26 are seated therein.

Extending around the tank 10 and inclined in an upwardly direction is a metal strip 27 which projects above the marginal edge of the flanged portion 17 of the cover sides 16. The strip 27 provides a trough 28 for receiving a liquid such as water into which the cover portion 17 extends to form an airtight seal between the interior and exterior of the tank 10.

The tank cover is rotated by a gear 29 and a pinion 30, the gear 29 being secured concentrically to the cover top 15 by an attaching flange 31. The pinion 30 is rotated by an electric motor 50 or some such means connected thereto by the shafts 32 and 33 and the gears 34 and 35.

The coating liquid for spraying the in-

terior of the pistons 26 is contained in the tank 10 and is moved by means of a conventional centrifugal pump 36 operated by a motor 51. The pump 36 draws the coating liquid from the interior of the tank 10 through an intake pipe 37 and exhausts the same under considerable pressure through a discharge pipe 38 leading to the interior of the tank 10 and terminating in a nozzle 39 which is positioned directly below the circular center line of the cups 23. The spray of coating liquid discharged from the nozzle 39 passes through the aperture 25 in the bottom of each cup 23 as it is moved thereover and strikes the top and sides of the piston 26 with considerable force so that as it drains back into the tank 10, all parts of the interior of the piston are covered by the coating. The cover may be rotated either continuously or intermittently and as each piston 26 is sprayed and passed beyond the reach of the spray, it may be removed and an uncoated piston placed in the cup 23 to be sprayed. The seal formed by the liquid-filled trough 28 and the pistons seating tightly against the bottom of the cups 23 provide a satisfactory means for preventing evaporation of the spraying liquid and for preventing the same from being passed to the exterior of the tank 10.

In operation, the pump 36 supplies a volume of liquid greater than is needed for the spray so that a portion of the same may be returned to the tank 10 below the level of the coating liquid through a secondary discharge pipe 40. The liquid returning to the tank 10 through the pipe 40, agitates the supply in the tank to keep the same thoroughly mixed.

The tank 10 is filled by pouring the liquid into a filler pipe 41 provided with a valve 42, the pipe being connected by means of a T connection to the intake pipe 37. While the tank is being filled, a valve 43 in the intake pipe 37 between the tank 10 and filler pipe 41 is closed, and a valve 44 in the discharge 38, is closed, so that all the liquid is pumped into the tank by the pump 36 through the secondary discharge pipe 40. When the tank is filled with a sufficient amount of liquid, the valve 42 in the filler pipe 41 is closed and the valves 43 and 44 are opened so that the liquid may be directed through the nozzle 39.

It may be desirable at times, to keep the pump 36 running and to shut off the spray. This is done by merely closing the valve 44 in the discharge pipe 38 and allowing all the coating liquid to be passed through the secondary discharge pipe 40.

It is apparent from the foregoing description that the present invention provides a means for coating cast parts with lacquer or similar coating compounds which is very efficient in its operation as the parts are completely coated and the machine is continuous which is a very desirable feature in quantity production.

It is to be understood that the present invention is not limited to a machine for pistons as it can be made to apply to any part which is desired to be coated or painted. It is also to be understood that the details of design of the pumping mechanism and cover rotating mechanism may be varied to meet existing conditions and that formal changes may be made in the specific embodiment of the invention described without departing from the spirit and substance of the broad invention, the scope of which is commensurate with the appended claims.

What I claim is:—

15 1. In a device for applying protective coatings to articles of manufacture, a supply tank containing a coating liquid, article supporting means rotatably mounted above said tank, means for rotating said article supporting means, means for conducting the coating liquid from said tank to be applied to said articles, and means exteriorly of said tank including said article supporting means forming a seal for preventing the escape of coating liquid from said tank.

20 2. In a device for applying protective coatings to articles of manufacture, a supply tank containing a coating liquid, a rotary cylinder provided with a plurality of apertures arranged concentrically therewith for receiving said articles, a stationary upwardly extending nozzle positioned below said cylinder, means for rotating said cylinder, means for conducting the coating liquid from said tank to said nozzle, said nozzle directing said coating liquid against each of said articles as they are moved thereover by said cylinder, and means exteriorly of said tank including said rotary cylinder forming a seal for preventing the escape of the liquid from said tank discharged from said nozzle.

25 3. In a device for applying protective coatings to articles of manufacture, a tank containing a coating liquid, a rotary cover for said tank formed with a plurality of openings arranged concentrically therewith, article receiving means positioned in said openings and having apertured bottoms, means for rotating said cover, a stationary upwardly extending nozzle within said tank positioned approximately below the circular center line of said article receiving members, a pump for conducting the liquid from said tank to said nozzle, the liquid stream exhausted from said nozzle passing through said apertured bottoms of said article receiving members to impinge against the surfaces of each article as it is moved thereover, and means exteriorly of said tank including said rotary cover forming a seal for preventing the escape from said tank of the liquid stream discharged from said nozzle.

30 4. In a device for applying protective coatings to articles of manufacture, a tank containing a coating liquid, a rotary cover

for said tank provided with means for supporting said articles, a circular outwardly extending flange surrounding said tank and secured thereto, a plurality of spaced vertically positioned rollers rotatably mounted on said cover for rotatably supporting said cover on said flange, means for rotating said cover, and means for directing a stream of liquid against said articles supported by said cover.

75 5. In a device for applying protective coatings to articles of manufacture, a tank containing a coating liquid, a rotary cover for said tank provided with article receiving members arranged concentrically thereof, a plurality of spaced horizontally positioned rollers rotatably mounted on said cover and engaging the sides of said tank for centering said cover concentrically of said tank, means for rotating said cover, and means supplied with liquid from said tank for spraying liquid against said articles supported by said cover.

80 6. In a device for applying protective coatings to articles of manufacture, a tank containing a coating liquid, a circular band surrounding said tank provided with a horizontal outwardly extending flange, a rotary cover for said tank provided with a plurality of article receiving members arranged concentrically thereof, a plurality of spaced vertically positioned rollers rotatably mounted on said cover to rotatably support said cover on said flange of said band, a plurality of spaced horizontally positioned rollers mounted on said cover to concentrically center said cover on said band surrounding said tank, means for rotating said cover, and means for pumping said liquid to successively spray each of said articles supported by said cover.

85 7. In a device for applying protective coatings to articles of manufacture, comprising a supply tank for a coating liquid, a cover for said tank having a top and a circular side wall rotatably positioned to support a plurality of said articles arranged concentrically therewith, stationary means within said tank adapted to successively spray said articles moved thereover by said rotary cover, a circular upwardly and outwardly extending member surrounding said tank and the circular wall of said cover forming a trough, and liquid in said trough, thereby forming an airtight seal between the interior and exterior of said tank to prevent the escape of coating liquid therefrom.

90 8. In a device for applying protective coatings to articles of manufacture, comprising a tank containing a coating liquid, a rotary cover over said tank supporting the articles to be coated, means for rotating said cover, a nozzle within said tank for coating said articles as they are moved by the rotation of said cover, a liquid pump for supply-
